DISPENSING BOTTLE TOP

Nicholas S. Martin, Brooklyn, N. Y.

Application March 5, 1935, Serial No. 9,473

4 Claims. (Cl. 215—25)

This invention relates to improvements in dispensing tops for containers and has for an object to provide a novel top which may be permanently secured to the neck of a bottle and when so secured may be considered as providing a non-refillable bottle.

A further object is to provide a dispensing top which may be used with a container until the contents thereof is exhausted and may then be

10 removed for use with successive containers.

A further object is to provide in such a dispensing top means to guide and disburse the contents from the central opening around the outside but within the body of the cap so that in the case 15 of liquids air may be allowed to enter so that the liquid may readily pour. In the case of powder this same member will tend to prevent clogging and will keep the powder loose so that it will flow freely through the device.

20 With these and other objects in view as will be apparent as the description proceeds, the device consists of the instrumentalities shown in the drawing wherein:

Figure 1 is a vertical section through a bottle 25 or the like showing my device mounted thereon, parts being in a normal position to close the apertures through the central portion thereof;

Figure 2 is a similar section with the parts shown as in dispensing position; and

30 Figure 3 is a section on the line 3—3 of Figure 2.

Referring particularly to the drawing the container or bottle 1 is provided with a neck 2 having threads 3 near the top thereof.

35 Mounted thereon is my dispensing device comprising a body portion 4 reduced as at 5 to form a spout with screw threads 6 upon which is mounted a removable closure 7. Within the spout is shown a member 8 having apertures 9.

40 This may be removed altogether from the spout if desired.

Positioned within the body portion is an annular member 10 having exterior fluted channels 11 and a hollow 12 adapted to fit over an annular 45 extension 13 of the threaded plug 14 mounted within the body of the cap. Apertures 15 are provided in this annular extension 13, and a pellet 16 is mounted to freely work back and forth within the extension and past the apertures.

50 At a centrally apertured plug 17 is screw

threaded at 18 into the member 14. A washer 19 is positioned between the apertured plug 17 and the threaded plug 14 and forms a shelf 20, or edge upon which the pellet 16 will rest in normal position. A washer 21 is interposed between the top of the body portion of the member 14 and the member 10 so that the member 10 will rest thereon when in normal position adjacent the apertures 15.

When in this normal position both the pellet 16 and the member 10 will be seated so as to close the apertures. Refilling the contents through the spout in this position is impossible. When in inverted dispensing position the apertures are open and the contents will flow through them and 15 around the fluted member being disbursed and broken up thereby as it enters the spout.

What I claim is:

1. In combination a bottle having a threaded neck and a dispensing cap therefor comprising a 20 body portion threaded to fit the threaded neck, a reduced spout therefor threaded to receive a removable closure, a removable plug mounted within the body portion to contact the top of the bottle neck, and having a hollow central extension 25 radially perforated, a centrally apertured plug partially closing the central extension, a pellet mounted within the extension and adapted to seat on the apertured plug to close the same when upright and to free the opening in dispensing position, and a freely movable plug mounted on the outside of the central extension and within the body portion adapted to seat and close the aperture in normal position when upright and to seat in the reduced spout and disburse the contents of the bottle when in dispensing position.

2. A dispensing cap comprising a body portion reduced at one end as a spout and having a central apertured plug, a pellet mounted within the plug to open or close the apertures and a movable cap mounted on the plug within the body portion and adapted to close the apertures in one position and to open the apertures and seat in the spout 45 as a disbursing guide in inverted position.

3. A dispensing cap comprising a body portion and a reduced spout, an apertured plug mounted within the body portion, and externally fluted disbursing member mounted to seat in the spout 50

in one position and to close the apertured plug in upright position.

4. A dispensing cap comprising a body portion adapted to fit a bottle neck, and having at the other end a reduced spout opening, an apertured plug mounted within the body portion and having an extension directed toward the spout, a freely movable pellet mounted within the exten-

sion adjacent the apertures, a freely movable exteriorly fluted member mounted on the extension within the body portion adjacent the apertures, the pellet and the fluted member being adapted to close the apertured member when in normal position and to free the apertures when in inverted dispensing position. 5
